UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-YOKE FOR RAILWAY-CAR DRAFT-RIGGING.

1,198,752.

Specification of Letters Patent. Patented Sept. 19, 1916.

Application filed April 17, 1916. Serial No. 91,588.

To all whom it may concern:

Be it known that I, JOHN F. O'CONNOR, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of 10 this specification.

My invention relates to improvements in draft yokes for railway car draft rigging.

One of the objects of my invention is to 15 provide a draft yoke which may be connected to the draw bar without the use of rivets or keys or other similar means passing through the draw bar and which will permit the removal of the draw bar without 20 disturbing the draft gear or other parts of the draft rigging.

Other objects will be apparent from the description of the invention hereinafter following.

25 In the drawings forming a part of this specification, Figure 1 is a side elevation of a draft yoke embodying my invention, the same being shown in association with other draft rigging parts. Fig. 2 is a plan view 30 and Fig. 3 is a front end view of the yoke.

In the drawings forming a part of this specification, the numerals 4—4 indicate draft members or parts of the car frame to which the draft rigging is applied; 5—5 35 front stop members secured thereto and 6—6 rear stop members. A draft gear 7 is shown in dotted lines in Figs. 1 and 2 of the drawings, the particular gear shown being of the friction type.

40 8 indicates a front follower; 9 the draw bar and 10 the draft yoke.

The draw bar is of the usual type and is provided with the upper and lower shoulders 11—11. The yoke comprises a pair of 45 loops arranged side by side, each loop comprising upper and lower limbs 12 and 13 respectively, connected at their rear ends by the preferably integral member 14 and at their front ends by the preferably integral 50 side plate 15. Each of the loops is provided at the rear end with suitable means as, for instance, the inter-engaging butts 16—16 having perforations for the passage 55 of the bolt 17 forming a hinged or pivoted connection between the two loops at their

rear ends. At their forward ends, the upper and lower limbs of both of said loops are provided with shoulders or gibs 117—117, the upper ones being adapted to engage the upper shoulder 11 of the draw bar and the 60 lower ones being adapted to engage the lower shoulder 11 of the draw bar.

When in assembled position, as illustrated in the drawings, the two loops of the yoke are held together at their forward 65 ends by means of the transverse bolt 18 passing through suitable perforations in the lower lug 19 with which the limbs of the yoke are provided near their forward ends. It will thus be seen that, when the two loops 70 are arranged in their assembled position side by side and the bolt 18 is inserted and the nut drawn home thereon, the draw bar is securely connected to the yoke so that, on forward movement of the draw bar, the 75 shoulders thereof are in engagement with the gibs of the yoke, thus drawing the yoke forward and compressing the gear in a manner readily understood. On rearward movement of the draw bar, the same may slide 80 rearwardly within the yoke without movement of the yoke, if desired. It will be understood that the yoke and gear may be supported in their position between the draft members by any suitable means as, for instance, the supporting plate 20 secured to the draft members.

In order to permit the spreading of the yoke to enable the forward withdrawal of the draw bar, the limbs are, on their outer edges 90 near the forward end and substantially opposite the front stop members, cut away or indented as shown at the numerals 21—21 in Fig. 2 of the drawings. By reason of this construction, the nut of the retaining 95 bolt 18 may be removed and the limbs of the yoke spread apart a distance sufficiently great to permit the forward withdrawal of the draw bar. The gibs upon the yoke are, as will be noted at the numerals 22—22 in 100 Fig. 2 of the drawings, outwardly inclined along their inner faces from their forward edges in order to make them substantially parallel with each other and with the draft members when they are spread apart, to 105 effect the ready forward removal of the draw bar.

In view of the standard sill spacing which rarely exceeds 12 $\frac{1}{2}$ in., it will be observed that I have provided a yoke which may be em- 110

ployed in the narrow space between the front stop members and which, at the same time, can be spread to permit the withdrawal of the draw bar without dismounting the gear or other parts of the draft rigging, and have made this possible with a yoke of the keyless type.

I claim:

1. In a draft yoke, a pair of loops arranged side by side, the said loops having at their forward ends gibs adapted to engage the shoulders of a draw bar, the said gibs along their inner faces being rearwardly and outwardly inclined, whereby the said inner edges of the gibs upon one loop are substantially parallel with those upon the other loop when the two loops are spread at their forward ends to permit the withdrawal of a draw bar.
2. In a draft rigging for railway cars, the combination with front stop members and a draw bar, of a draft yoke, a draft yoke comprising a pair of loops arranged side by side, each loop being provided at its forward end with gibs to engage the draw bar's shoulders and being adjacent the front stops indented to permit the separation of said loops whereby the draw bar may be forwardly withdrawn between the opposed gibs upon said loops.
3. In a draft rigging for railway cars, the combination with front stop members and a draw bar, of a draft yoke comprising

two members arranged side by side swingingly connected at their rear ends and having at their forward ends gibs to engage the draw bar and being provided with means to prevent accidental spreading, each of said members being near the front stop members indented to permit their spreading to effect the forward removal of the draw bar between the gibs upon the removal of the means securing the said two members together.

4. In a draft rigging for railway cars, in combination, a draw bar, stop members and a draft yoke, the draft yoke comprising a pair of loops, the said loops being swingingly connected at their rear ends, the draw bar being provided with shoulders and each of said loops having gibs to engage said shoulders, the gibs upon each loop being along their inner edges rearwardly and outwardly inclined, each of said loops being indented near its forward ends, substantially opposite the adjacent front stop member, whereby, upon the spreading of the said loops at their forward ends, the draw bar may be forwardly removed between the inner edges of the opposed gibs upon said loops.

In witness that I claim the foregoing I have hereunto subscribed my name this 12th day of April, 1916.

JOHN F. O'CONNOR.
